STOP MOTION

Robert H. Lawson, Pawtucket, R. I., assignor to
Hemphill Company, Central Falls, R. I., a
corporation of Massachusetts

Application March 27, 1936, Serial No. 71,192

6 Claims. (Cl. 66—157)

This is an invention for application to all types of stop motions for textile machinery or the like and is herein described and illustrated relative to a knitting machine for purposes of disclosure and not by any reason of limitation. Among the 5 objects of the invention is the provision of a control for stopping the machine when the electric current fails for any reason, this provision for stopping the machine being in addition to the usual stop motion control set in operation by 10 detents controlled by the yarn, fabric, etc. Another object of the invention is that of providing means for setting the electrically controlled throw-off device prior to engaging the clutch of 15 the machine so that the machine will not be started and immediately stopped in the event the operator has not completely prepared the machine for running prior to engaging the clutch. The throw-off device has a lever engaged by a latch or other retaining means which lever will be 20 released upon stopping of the machine and said throw-off device also causes current to be shut off from the circuit. The lever will pass by the latch and after current is discontinued, the latch will return to its normal position and will prevent 25 a reverse movement of the lever. A new device has been attached to the end of the lever for maintaining the latch open until the lever has passed by it to be locked by the same.

In the drawings:

Fig. 1 is an elevation showing the general construction of the clutch, throw-off lever, feeding device, the latch for the throw-off lever and the no current stop;

Fig. 2 is an elevation of that mechanism shown in Fig. 1, parts being in section, and showing the device as seen from the end;

Fig. 3 is a detail, some parts being shown in section, of the latch box, latch and the no current stopping means attached thereto;

Fig. 4 is a detail view corresponding to Fig. 3 but showing the latch and other parts in a position after the machine has been stopped;

Fig. 5 is a semi-diagrammatic view showing the electrical hook-up in applying the invention to a 45 typical multi-feed knitting machine.

In stop mechanisms previously used on knitting machines or other textile machinery in which stopping devices are actuated by completing a circuit as by the dropping of yarn controlled 50 detents or other similar devices, the failure of current for any reason whatsoever will immediately render the stop motion inoperative. This is apparent since the machine continues to run except when a circuit is completed, and of course,

if current fails due to breaking a wire, a poor connection, or for any other reason, no circuit will ever be completed. In the device herein disclosed a solenoid has been connected in the circuit in such a manner that it holds a spring controlled element in one position so long as current is available. Just as soon as current fails this spring controlled element will throw-off the driving connections of the machine thereby stopping the same. As soon as current is available 10 this additional means for stopping the machine has no effect at all and does not influence the rest of the stop motion in any respect.

According to the usual construction of machines of this sort an electrically controlled latch 15 or similar device holds a belt shifting or a clutch controlling lever in one position for driving the machine until action of one of the stop motions releases said lever which immediately shifts the belt to a loose pulley or disengages the clutch by 20 means of a heavy spring. With such a construction the operator has to grip the lever and pull it to an operative position whereupon the latch or other electrically controlled retaining means for the lever will be engaged and will hold the 25 clutch in engagement or the belt on a driving pulley as the case may be. If it should so happen the machine had stopped due to some actuation of the stop motion and the difficulty which caused such stopping were not completely remedied, the 30 lever would immediately be released and would fly back to its original position. This would involve a useless starting of the machine for part of a revolution and needless wear and tear on the operating parts of the machine and of the stop 35 motion. To overcome this difficulty a separate controlling lever is provided so that a part of the throw-off mechanism which would be latched in operative position by the electrically controlled latch or the like may be pulled to an active position without disturbance of the belt shifter or clutch. If any stop motion is still acting upon the electrically controlled latch, this preliminary movement of part of the throw-off mechanism will show that fact to the operator. 40 The latch will not retain the said throw-off means and it will thereupon be necessary for the operator to remedy all difficulties attendant upon the original stopping of the machine before the throw-off device can be set. Up to this point 50 there has been no disturbance of the driving mechanism for the machine and no false starting as explained above. When the throw-off device can be set it is safe to pull in the clutch and start the machine.

Due to the construction of parts involved the end of the throw-off lever which is engaged by the electrically controlled latch is of such a length that it passes by the latch and would not easily 5 move back and depress the latch on the return movement. Another member has been added to the end of this lever for holding the latch depressed after the end of the lever moves past it, but is so constructed that it has no effect when 10 the lever is in latched position. Referring to the figures of drawings the side of the machine frame is indicated at 1, a bracket projecting at 2 carrying a casing 3, cover 4, guard 5 and a spacing or supporting element 6. The drive shaft 15 7 is driven through a clutch generally indicated at 8, Fig. 2, one part of which is driven by a belt drive to pulley 9. The end of the shaft carrying pulley 9 is supported within a bearing at 10 at the upper end of an angular extension 11. These 20 elements are more or less conventional on machines of this type and have not been illustrated in detail for that reason.

The clutch is to be operated by means of a forked lever 12 which projects up through an 25 opening in the cover to the casing, terminating in a handle 13. The forked ends 14 and 15 of this lever are free to turn upon a spindle 16 which extends through bearings 17 and 18 in opposite sides of the casing. This lever 12 has slotted 30 openings at 19 and 20 which engage about the pins 21 and 22 which project at either side of a clutch operating collar and it is evident that movement of the lever 12 will move the collar and thus engage or disengage the clutch at the 35 will of the operator.

Another forked lever 23 is fixed to spindle 16 and projects downwardly as shown at 24 having a spring 25 attached at the lower end of this projection and also to one of the hooks 26 on bracket 40 27 rigidly connected to the support 6. This bracket 27 is formed on an angle as indicated so that different adjustments of the spring may be obtained by hooking it to different ones of the hooks 28. The forked ends of lever 23 terminate in 45 hooks 28 and 29 which partially encircle the ends of the pins 21 and 22 so that movement of the lever 23 under action of spring 25 will throw the clutch out of active engagement, but the said lever, as will later be explained, can be moved to 50 the opposite position against the tension of spring 25 without so moving lever 12 or the clutch. Another lever 30 herein called the throw-off lever is attached by set screw 31 or by any other suitable means to the end of spindle 16 and rigidly 55 moves therewith. The end of this lever 30 terminates in a widening part 32 which is latched in the position shown in Figs. 1 and 3 by a latch 33 and thus prevents action of the spring 25 throwing the clutch out of active engagement. 60 As soon as latch 33 is withdrawn from the end of lever 30, as will happen whenever any one of the several stop motions on the machine is moved to complete a circuit, the spring will move all the elements 23, 12, 30 and the clutch to 65 the opposite position from that shown in Fig. 1 whereupon the machine will stop.

The spindle 16 projects to the opposite side of the casing and has fixed thereto a lever arm 34 carrying a roller 35 which engages one projecting arm 36 of the switch blade 37, Fig. 5. This blade is pivoted at 38 on a bracket 39 and allows current to flow through the various stop motion connections or to be excluded therefrom depending upon whether or not the switch blade is in 75 contact with element 40. When the clutch is

engaged this switch will be closed against the action of a spring 41, but when the stop motion is actuated lever 34 will be moved throughout a sufficient angle to allow the spring to open the switch and thus exclude current from the stop motions until the machine is to be started again.

A lever 42 is pivotally mounted at 43 and projects inwardly of the casing at 44 to terminate in a toe portion 45 which engages extension 24 of the forked lever 23. This lever has a spring 46 which is connected at its lower end to the element 6, this spring being merely for the purpose of holding the lever in opposite position to that shown in Fig. 1. This lever is used to set the throw-off mechanism prior to engaging the clutch. In previous constructions the lever 12 was employed for both these functions and if there was any tendency for the machine to stop again due to any one of the detents supported by the yarn being in position for completing the circuit, just as soon as switch 37 was closed, the latch 33 would be withdrawn again so that the stop motion would stop the machine. Such a method of operation necessitated starting the whole machine thus consuming a great deal of power and subjecting the machine to shock of starting and stopping for a partial revolution or so. By the present system of operation lever 42 is used to set throw-off arm 30 against the tension of spring 25 and if latch 33 holds these elements in position, the clutch 36 may safely be engaged and the machine started. If throw-off lever 30 is moved to a position in which it should be held by latch 33 and there is any further tendency of stop motions to complete a circuit and stop the machine, or in the particular construction herein shown, if there is a complete lack of current, the throw-off lever 30, etc., will not remain in position and the operator will look for further trouble before engaging the clutch and starting the machine. This 40 comprises a very satisfactory mechanism for stopping the machine and for testing the same prior to starting it again, but does not make it necessary to employ any power or subject the machine to short, jerky periods of operation.

The latch 33 is briefly any electrically controlled latch or tripping mechanism which might be employed to hold the lever 30 and to release the same upon disturbance of any electrical circuit such as employed in these stop motions. In the 50 particular example herein shown a box or casing 47 is attached to a support 48 which projects from the frame of the machine, this casing carrying latch 33 pivoted at 49 and being urged into the position shown in Fig. 3 by a spring 50. The 55 latch has projecting pins 51 at either side which engage in the slots 52 in wings 53 one of which is pivoted at 54 within and to the casing at either side of the same. An armature or plate 55 is pivoted at 56 and a spring 57 tends to maintain the same up against stop pin 58 as shown in Fig. 3. When in lower position to which it is drawn by the magnetized cores 59 whenever any one of the detents drops to complete a circuit, the latch is swung down to the position of Fig. 4 and the wings 53 will be moved back by pins 51 since their lower ends are no longer held by elements 60, one at either side of the device, which lock the wings and through them the latch, whenever the cores 59 are demagnetized.

The lever 30 is widened out at 32 and will be engaged by the latch to be held in the position of Fig. 3, but when released to the position of Fig. 4, the end of the lever passes beyond the latch so that the same may spring back to its 75

original position under the influence of the spring 50. There would be no harm in this if current was still maintained in the circuit and the armature 55 as well as the elements 60 attached thereto were held in lower position. However just as soon as the lever 30, spindle 16 and switch 37 move through a part of their travel, the current will be cut off so that spring 57 will immediately move the elements 55 and 60 back 10 to uppermost position as soon as the end 32 of the lever disengages latch 33. The latch will then be locked in position so that the lever 30 can not be swung past it for the purpose of setting the throw-off device to start the machine. 15 To overcome this difficulty, a plate 61 is hinged to lever 30 at 62, said plate having a curved part at 63 and a downwardly projecting hook 64. The hook 64 engages the back of bracket 48 so that when the lever 30 is moved under the influence 20 of spring 25, the plate will be retained in position over latch 33 as illustrated in Fig. 4. Even though armature 55 is released by demagnetizing the cores, the latch will not be locked until the lever has been moved to extreme position as in 25 Fig. 3. This plate 61 avoids lengthening the lower part of lever 30, such lengthening being impossible due to restricted space at this part of the machine. The spring 65 attached at 66 to the plate and at 67 to the lever tends to draw 30 the plate into alignment with the end of the lever.

The stop motion which has been described up to this point as well as all stop motions of the prior art of which we are aware, functions to 35 stop the machine only in the event current is available. An additional mechanism has been attached to that already disclosed for the purpose of stopping the machine upon failure of current for any reason whatsoever. This no current stop as it is called herein may be applied to any conventional stop motion of similar nature to that herein disclosed, and would also be very desirable on all similar types of machines and is in no way limited to knitting machines alone. 40 The box 47 has attached thereto a bracket 68 having an angular extension 69 connected thereto but insulated from the first bracket and a second extension having a solenoid device 70 very similar to that employed to actuate the latch 33. A plate or armature 71 is hinged at 72 and 45 has a stop 73 projecting from the lower side thereof which may strike against a part 74 of the extension 69. The bracket 68 extends outwardly and downwardly at 75 and has a spring 76 attached thereto which is also attached at a connection 77 beneath the armature 71 and the extending part 78 which projects therefrom for a purpose presently to be described. The projection 78 has a slot 79 adjacent the upper end 50 which engages about a pin 80 projecting from armature 55 and through the bracket 68. When current is available at the machine it is continuously flowing through the coils within the solenoid 70 and will maintain elements 71 and 55 78 in the position of Fig. 3 against the tension of the spring 76.

When this no current stop device is thus controlled the function of the mechanism within box 47 is completely independent thereof and works to stop the machine upon any disturbance 60 of the yarn controlled detents and the like. However, in the event current should fail, spring 76 would immediately draw the attached members downwardly to the position of Fig. 4 and 65 through the action of the slot 79 on the pin 80,

would release latch 33. Of course, this happens whenever switch 37 is opened upon stopping of the machine, but it is the main object of the mechanism described to stop the machine by releasing lever 30 whenever current fails for unexpected reasons. Otherwise the machine would continue in operation without any stop motion affecting the same and considerable damage might be done to parts of the machine in case of broken butts on some instrumentalities, or in 10 the event of broken yarns, defective fabric might be knitted for a considerable period of time.

Now referring to Fig. 5 the general description of the wiring hook-up for the machine will be explained. Any source of current might be used, the most satisfactory being that of the usual light circuit, a plug 81 conveying the same to a transformer indicated at 82 for the usual purpose. The transformed current is carried up to switch 37, and if this switch is closed, will be carried to ring 83 located at the top of the machine, and having stop motions preferably actuated by tension relieving take-up arms or sweeps such as form the subject matter of co-pending United States application Ser. No. 81,897. A series of 15 detents 84 equivalent in number to the number of yarns being used in the machine would be mounted on supports 85 to contact ring 83 and complete a circuit through ground as indicated in the event of any unusual condition with respect to the yarn at that particular detent. The current flows from ring 83 to a second ring 86 having guides 87 and detents 88 of conventional type mounted on individual supports 89. These 20 detents are out of contact with ring 86 when the yarn is passing through guide 87 properly but upon any unusual happening, will drop to make a contact with the ring and complete a circuit through the ground as illustrated. Current is 25 carried from a second ring to a third ring 90 adjacent the needles of the knitting machine and at that point there are two detents or contacting elements 91 and 92 either of which may complete a circuit through ground to stop the machine. Current then passes down a lead 93 to 30 terminal 94 thence through another connection 95 to solenoid 70. From the solenoid current passes through wire 96 to a terminal 97 and back to the transformer completing the circuit. Another wire 98 connects at the terminal 97 and 35 provides a source of current for the coils within the box 47. These coils are grounded as shown to the frame of the machine and it is obvious that this solenoid within box 47 will be energized whenever any one of the detents above 40 described grounds the current in rings 83, 86 or 90 to the frame thus actuating latch 33 and stopping the machine. The solenoid within box 47 45 may be grounded directly to the frame through the box or as has been illustrated in Figs. 1, 2, 3 and 4 may be grounded through a terminal 99 back to the frame. In this event a wire would have to be run from a post under the box to the said terminal. As illustrated in Figs. 2, 3 and 4 the end 75 of bracket 68 carries an insulating piece 100 through which terminals 94 50 and 97 pass. This forms a convenient place for 55 attaching the various wires necessary.

The invention has been described in more or less specific terms in order to give a clear illustration of the manner in which the device may be constructed and operated, but it is evident that many changes might be made and that the principles of the invention may be applied to many stop motions which are quite varied from the 75

particular one shown herein. The specific disclosure of the case is to be considered as illustrative only and the scope of the invention is not to be limited except by the claims appended hereto.

5 I claim:

1. In a stop motion the combination of electrically actuated means for releasing a driving mechanism to render the same inoperative, an electrical circuit connected to a source of current and to said electrically actuated means, detents for completing a circuit through said means upon conditions requiring the operation of the stop motion, and electrically controlled means in the circuit operated upon failure of current to control said electrically actuated means.
- 10 2. A stop motion having in combination an electrically controlled latch including a solenoid to withdraw the latch at certain times, an electrical circuit connected to said solenoid, a ground on said solenoid and means functioning with said circuit to complete a ground therefrom to that of the solenoid, another solenoid within said circuit and continuously under the influence of current flowing therethrough, said second mentioned solenoid having means connected thereto for withdrawing said latch independently of the action of the said first mentioned solenoid.
- 15 3. A stop motion having in combination an electrical circuit normally connected to a source of current and an electrically controlled latch connected to function in said circuit said latch being constructed to be released only upon actuation of means for completing the flow of current through said circuit, another connected circuit and control for said latch normally maintained in a position not to affect the latch so long as current is flowing, but operative upon failure of current to release the said latch.
- 20 4. In a machine of the type described, a stop

motion including electrically controlled means for initiating the stopping of the machine, an electrical circuit, a solenoid connected to said circuit and operable to actuate said electrically controlled means, a plurality of detents within the circuit and movable for completing the circuit to energize said solenoid, another solenoid within said circuit normally energized when the machine is running and means functioning when current fails to flow in said circuit and acting directly on said electrically controlled means to move the same for stopping the machine.

5. In a knitting machine, a stop motion having in combination power throw-off means, means for holding said throw-off means in one position, a solenoid effective to withdraw said last mentioned means and to release the throw-off means, said solenoid being connected to a circuit capable of being completed whereby the solenoid will be energized upon movement of a yarn controlled detent, another solenoid functioning to withdraw said means for retaining the power throw-off means whenever current ceases to flow in the circuit.

6. A stop motion for a knitting machine having in combination power throw-off means, a latch for retaining said throw-off means in engaged position, an electrical circuit, a series of detents for completing said circuit upon an abnormal condition in the yarn passing through said detents, a solenoid in said circuit and energized upon movement of said detents to withdraw said latch, a second solenoid in said circuit energized when current is present in the circuit, means controlled by said second solenoid and inactive to withdraw said latch when current is present, but so constructed as to release the latch when current fails to flow in said circuit.

ROBERT H. LAWSON.
